UNITED STATES PATENT OFFICE

CHARLES F. MILLER AND SETH W. BRUNDAGE, OF MIAMI, FLORIDA

CONVERTIBLE AWNING AND SHUTTER

Application filed December 11, 1928. Serial No. 325,228.

The invention relates to protective devices for the window openings in buildings.

The principal object of the invention, generally stated, is to provide means adapted to serve either as an awning for shading the window against excessive light and protecting it against rain, or for closing the window opening entirely to form a protection in the event of a severe storm or in case it is desired to leave the building unoccupied for a considerable time.

An important object of the invention is to provide a convertible or combined awning and shutter which is of sectional formation and which is adapted to be partially folded or collapsed when in its elevated or awning forming position with the parts or sections maintained in a certain fixed relation.

Another object of the invention is to provide a protective device of this character having novel means for mounting the same upon the building and having other novel means pivotally or movably connecting the sections or parts in such manner that they will move into the proper overlapping collapsed relation when the device is shifted to awning forming position, and so that the parts or sections will be brought into alignment for forming a shutter or closure for the opening when the device is lowered.

Another important object of the invention is to provide a device of this type in which the sections are so connected that when the device is raised to awning forming position one section will underlie the other and act as a substantial brace therefor which will assist in maintaining the device in the awning forming position with very little strain upon whatever means is provided for holding it elevated.

Another object of the invention is to provide a device of this character in which the means for raising the device from shutter to awning forming position is extremely easily operable so that the operation may be carried out by a person having very little strength, the actuating means being, moreover, so positioned as to be manipulated from the inside of the building without it being necessary to open the sash or sashes.

An additional object of the invention is to provide a structure of this character which will be simple and inexpensive to manufacture, easy to install and operate, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is an elevation of the device from the outside of the building showing it in shutter forming position.

Figure 2 is a vertical cross sectional view taken on the line 2—2 of Figure 1 with the valance omitted.

Figure 3 is a view similar to Figure 2 showing the initial movement of the endmost section when the device is being raised into awning forming position.

Figure 4 is a similar view showing the position of the parts during the raising movement but prior to the final location.

Figure 5 is a similar view showing the device raised fully into its awning forming position.

Figure 6 is a vertical sectional view taken on the line 6—6 of Figure 2 showing an inside view of the device in shutter forming position.

Figure 7 is an elevation of the window from the inside of the building showing the location of the parts, and

Figure 8 is a detail view showing the holding means for the raising cable and the device for holding the shutter closed.

Referring more particularly to the drawings, the numeral 1 designates the wall of a building having a window opening 2 therein within which is mounted the window frame 3 which is equipped with sash or sashes 4 of the sliding or other preferred type.

In carrying out the invention, we provide a protective device indicated generally by the numeral 5 and comprising upper and lower sections 6 and 7 which are preferably rigid in construction and which may be

formed of any suitable material such as metal or wood and which may be finished in any desired manner to have a neat and attractive appearance and to be capable of withstanding the weather. If these sections be formed of wood they may well be covered with canvas or the like to exclude moisture from the material and, in any event, the section 7 may be provided with a valance 8 so that it will 5 resemble a conventional awning, the attractiveness being consequently enhanced. The upper section 6 is pivotally mounted above the window opening as by means of a hinge or hinges 9 which are preferably secured upon 10 a strip 10 secured to the outside of the building wall, an angular metallic trough-like guard 11 being provided which extends over the hinged end of the section 6 for the purpose of excluding water from the joint and 15 preventing rain from beating in behind the device.

The section 7 of the protector is connected with the section 6 by a peculiar type of link connection whereby it may move from a position in alinement therewith when in closed position, as shown in Figures 1 and 2 into overlapping relation thereto as shown in Figure 5. In actual practice this connection comprises arms 12 pivoted to the sections 6 20 and 7, it being a preferred construction that these arms form the sides of a rectangular frame comprising horizontal connecting portions 13 and 14 pivoted to the sections as by means of clips 15 or the like. However, this 25 structure is simply suggestive as alternative arrangements will be readily apparent. The adjacent ends of the sections 6 and 7 are preferably stepped as indicated at 16 so as to provide a lapped joint when the sections are in 30 alinement to form a shutter.

The mounting further comprises brace arms 17 pivoted at 18 upon the window frame or side of the building and pivotally connected with the lower end portion of the section 45 7. While different mechanical expedients may be resorted to, these brace arms 17 may simply constitute the sides of a U-shaped frame-like member including a horizontal bight portion 19 disposed against the inner 50 side of the section 7 and pivoted with respect thereto as by means of bearing clips 20, shown most clearly in Figure 6. To facilitate the mounting of the clips 15 and 20 the intermediate portions of the inner or undersides of 55 the sections 6 and 7 are represented as partially cut away or recessed at 21 and 22, respectively. However, it should be understood that this is a mere refinement and does not affect the spirit of the invention to any 60 material extent.

The means for raising the device from the lowered or shutter forming position shown in Figures 1 and 2 into the elevated or awning forming position shown in Figure 5 preferably 65 comprises a flexible member, such as a

chain or the like 23, with a cord attached to the end, and which is dead ended at 24 at the lower end of the section 6, which is trained beneath a guide pulley 25 and about a guide pulley 26, both of which are on the underside of the section 7, which is trained over a guide pulley 27 on the underside of the upper end portion of the section 7, which then passes over a guide pulley 28 mounted in an opening 29 at the upper end of the section 6, and which then passes through an opening 30 at the top of the window frame, it being preferable to provide a guide pulley 31 at the inner end of this opening and an additional guide pulley 32 on the inside of the window frame adjacent the opening. The free end of the flexible member is intended to hang down within the room in convenient position to be grasped and pulled by the operator when it is desired to shift the device into awning forming position. At some convenient location, we prefer to mount on the window frame a fixture 33 which embodies an eye 34 through which the flexible member extends, the flexible member being equipped with a key or pin 35 at its free end adapted to be passed through the proper one of the links in the chain for maintaining the flexible member under tension with the protective device in raised or awning forming position.

The means for lowering the device from awning to shutter forming position is shown as comprising simply a flexible member such as a chain 36, with a cord 37 attached to the free end thereof, the cord passing through and the chain being adapted to pass through an opening 38 in the window frame. The fixture 33 is shown as having an opening 39 therein registering with the opening 38 for the passage of the cord 37 and chain 36, the intention being that when the device is in lowered position as shown in Figures 1 and 2 a pin or key 40 on the end of the cord 37 may be passed through whichever link of the chain 36 taut and prevent the device from being opened from the outside of the building.

In the operation, when the device is in shutter forming position, the sections 6 and 7 are in alinement with the latter below the former and with the stepped portions 16 interfitting to form a weather-proof joint. The chain 36 is held under tension as above described for holding the device secure so that it could not be opened by an intruder without destroying the device and making sufficient noise to attract attention. In this way the device is of particular advantage as a protection when the building is to be left unoccupied for an appreciable time. Of course it is readily apparent that when the device is in this position it will serve as an adequate protection against hurricanes and other violent storms which might blow in an

130

unprotected window and cause serious damage.

When it is desired to use the device as an awning, it is first necessary to disengage the 5 pin or key 40 from the chain 36 so as to release the holding action. The operator then grasps the cord at the inner end of the flexible member 23 and pulls upon it. As this flexible member is confined between the stepped portions 10 16, as indicated in Figure 2, the first effect will be to throw out the section 7 so that it will no longer be in alinement with the section 6. This initial movement is well disclosed in Figure 3 of the drawings. As 15 the pull upon the flexible member is continued, the member 7 is moved upwardly, the arms 17 pivoting at 18 and 20, and the frame member including the arms 12 pivoting at the clips 15. The section 6 remains in depending 20 vertical position during this movement and it will be seen that the section 7 swings first upwardly and outwardly until the arms 12 are horizontal, and then continues to swing upwardly but inwardly toward the wall of 25 the building until the upper end of the section 7 approaches a position beneath the water-shed 11. This position is illustrated in Figure 4. As the pull is continued, the lower end of the section 6 swings outwardly 30 and into engagement against the underside of the section 7, at the same time that the section 7 is forced home beneath the watershed 11. The engagement of the section 6 beneath the section 7 will brace the section 7 and assist in 35 holding it in its inclined elevated position. The key or pin 35 carried by the cord forming the end of the flexible member 37 is then passed through the proper one of the links in the chain portion thereof for maintaining 40 this flexible member under tension and consequently holding the device in its elevated or awning forming position. Owing to the fact that the section 6 engaging flatly against the underside of the section 7 tends to hold 45 the section 7 against dropping down, it is apparent that very little strain will come upon the flexible member 23. However, the tension will be sufficient to hold the parts securely against movement and consequent rattling 50 in the event of a wind storm.

When it is desired, as for example upon the approach of a storm to lower the device to protect the window, it is first necessary to disengage the key or pin 35 from the flexible 55 member 23, whereupon gravity may be sufficient to lower the parts. If not, it is a simple matter to apply a slight pull upon the flexible member 37, preferably while maintaining a grip upon the flexible member 23 60 so that the sections 7 and 6 will swing down gently into their alined position closing the window opening, subsequently to which the flexible member 37 should be pulled taut and the key or pin 40 inserted through the proper 65 link in the chain portion 36.

From the foregoing description and a study of the drawings it will be apparent that we have thus provided a simply constructed and easily installed device which will efficiently perform the functions for which it is intended. It should be noted that owing to the particular and peculiar arrangement of the flexible member for raising purposes and the pulleys with which the same cooperates, ample leverage is obtained for effecting the raising in a very easy manner and without requiring the exercise of any great degree of strength, this making the device particularly suitable for use on dwelling houses where it may be possible that the device will need to be manipulated perhaps by a woman or a child. When the device is in its awning forming position it will act the same as any other awning in excluding undesired light and in protecting the window opening against moderate rain and wind. The advantages of the device when in shutter forming position have already been discussed and a repetition thereof is unnecessary. It is believed that the construction, operation and advantages will be readily apparent to one skilled in the art without further explanation.

While we have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, we 105 claim

1. In a protective device for a window opening, a relatively rigid member formed of sections, one section being pivoted above the window opening, brace means pivotally connected with the building wall and the lower end portion of the other section, arm members pivotally connecting the lower portion of the first named section with the upper portion of the second named section whereby 110 said sections are capable of relative swinging movement and whereby the upper edge of the second named section is caused to move in an arcuate path from adjacent the lower edge of the first-named section to adjacent the upper edge thereof.

2. In a device of the character described, a protecting member formed of upper and lower sections, the upper section being pivoted at the top of a window opening, brace means pivotally connected with the lower section and with the building wall, arm means pivotally connecting the upper portion of the lower section with the upper section and means connected with both sections for 115 120 125 130

swinging said sections into inclined positions above the window opening, said brace and arm means being adapted to cause the inner face of the lower section to be disposed in contiguous overlapping relation with the outer face of the upper section when the sections are disposed in inclined positions.

3. In a device of the character described, a protecting member formed of upper and lower sections, the upper section being pivoted at the top of a window opening, brace means pivotally connected with the lower section and with the building wall, arm means pivotally connecting the upper portion of the lower section with the upper section and means connected with both sections for swinging the lower section outwardly and upwardly into inclined position above the window opening and for subsequently swinging the upper section outwardly into engagement beneath the lower section, said arm means permitting upward movement of the lower section independently of movement of the upper section.

25 4. In a device of the character described, a protecting member formed of upper and lower sections, the upper section being pivotally mounted above the window opening for vertical swinging movement, arm members pivotally connecting both sections, and means for swinging the lower section outwardly and upwardly into inclined position extending downwardly from the top of the window opening and for subsequently swinging the upper section outwardly whereby the outer face of the upper section is brought into contiguous relation with the inner face of the lower section beneath the lower section.

40 5. In a device of the character described, a protecting member formed of upper and lower sections adapted to be disposed in substantially vertical alinement to serve as a shutter for a window opening and in inclined overlapping relation to serve as an awning therefor, the upper section being pivotally mounted above the window opening for vertical swinging movement, arm members pivotally connecting the lower section to the upper section, and means for swinging said sections into inclined positions adjacent the top of the window opening, said arm members being adapted to cause the upper edge of the lower section to move upwardly relatively to the lower edge of the upper section when the sections are actuated to assume overlapping relation.

55 6. In a device of the character described, a protecting member formed of pivotally mounted independently movable adjoining sections, one section being pivoted at the top of a window opening, means connected with the sections for initially moving one section and for subsequently moving the other section to bring said sections into lapping relation in inclined position at the top of the window

opening, said sections being movable to depend in alinement to form a closure for the window opening.

In testimony whereof we affix our signatures.

CHARLES F. MILLER.
SETH W. BRUNDAGE.
